UNITED STATES PATENT OFFICE.

JAMES TAYLOR AND JOHN ROBINSON, OF LANCASTER, ENGLAND.

POCKET IMPLEMENT.

SPECIFICATION forming part of Letters Patent No. 699,987, dated May 13, 1902.

Application filed September 13, 1901. Serial No. 75,316. (No model.)

To all whom it may concern:

Be it known that we, JAMES TAYLOR and JOHN ROBINSON, subjects of the King of Great Britain, residing at Lancaster, England, have 5 invented certain new and useful Improvements in Pocket Implements, of which the following is a full and complete specification, such as will enable those skilled in the art to which it appertains to make and use the same.

10 This invention relates to a combination pocket implement for use as a match-igniter, pipe-cleaner, and for various other purposes; and the object thereof is to provide an improved device of this class which is simple in 15 construction and operation and which may be conveniently carried in the pocket and which is also comparatively inexpensive, while being well adapted to accomplish the result for which it is intended.

20 In the accompanying drawings, forming part of this specification, in which like letters of reference designate corresponding parts in the several views, Figure 1 is a plan view of the simplest form of our improvement and 25 showing the device intended for use as a match-striker, pipe-cleaner, &c. Fig. 2 is a side view of the device as shown in Fig. 1. Fig. 3 is a section on the line $\alpha\alpha$ of Fig. 2.

In the practice of our invention we provide 30 an implement of the class specified which is primarily intended for a match-striker, pipe-cleaner, and tobacco-packer, and this implement comprises a main body portion a , composed of sheet metal, larger at one end than 35 at the other and tapered from one end to the other and triangular in cross-section and open at one side whereby two side walls a^2 are

formed, which are provided on their inner surfaces with transverse serrations or teeth a^3 , forming roughened surfaces which serve 40 as a match-igniter, and the side walls a^2 are brought together at the larger end, and pivoted thereto, as shown at a^4 , is a circular head or plate a^5 , by means of which tobacco may be packed in the bowl of a pipe. The part a 45 of this device may be used, as will be readily understood, for cleaning the bowl of the pipe, and the device may be carried in the pocket or in any suitable receptacle.

This device is simple in construction and 50 operation, and it will be apparent that changes in and modifications of the construction herein described may be made without departing from the spirit of our invention or sacrificing its advantages.

Having fully described our invention, what we claim as new, and desire to secure by Letters Patent, is—

A tool or implement of the class described comprising an elongated body portion, V- 60 shaped in cross-section and pointed at one end, the inner walls of the sides thereof being provided with roughened surfaces, and a head or plate pivoted to the larger end thereof, substantially as shown and described. 65

In testimony that we claim the foregoing as our invention we have signed our names, in presence of the subscribing witnesses, this 3d day of August, 1901.

JAMES TAYLOR.
JOHN ROBINSON.
